By James W. Parker, Atty.

UNITED STATES PATENT OFFICE.

JAMES G. PENNYCUICK, OF TORONTO, CANADA.

DESIGN FOR A PRISM-LIGHT.

SPECIFICATION forming part of Design No. 27,340, dated July 13, 1897.

Application filed June 15, 1897. Serial No. 640,927. Term of patent 14 years.

To all whom it may concern:

Be it known that I, JAMES G. PENNYCUICK, a citizen of the Dominion of Canada, residing at Toronto, in the county of York and Province of Ontario, Canada, have invented and produced a certain new and useful Design for Ornamental Prism-Lights, of which the following is a description.

My invention relates to a design for prism-lights.

It is illustrated in the accompanying drawings, wherein—

Figure 1 shows a perspective view of a prism-light containing my design. Fig. 2 is a cross-section.

Like parts are indicated by the same letter in all the figures.

A is the body of the prism having the plain

side B and the prism side C, with the prisms D D arranged thereon substantially parallel to the hypotenuse of the triangle. The prisms are shown as of certain sizes, angles, and numbers; but the essential feature of my invention, however, is a triangular prism-light having a practically smooth surface on one side with a prism-surface on the other side, said prisms being substantially parallel to the hypotenuse of the triangle.

I claim—

The design for a prism-light substantially as shown and described.

JAMES G. PENNYCUICK.
